CLAIM

The ornamental design for an electronic device, as shown and described.

DESCRIPTION

FIG. 1 is a front, top, right perspective view of an electronic device showing our new design;

FIG. 2 is a rear, top, left perspective view thereof;

FIG. 3 is a front elevational view thereof;

FIG. 4 is a rear elevational view thereof;

FIG. 5 is a right side elevational view thereof;

FIG. 6 is a left side elevational view thereof; and

FIG. 7 is a top plan view thereof.

FIG. 8 is an enlarged front elevational view of a portion of the electronic device along the lines 8-8 and 8'-8' of FIG. 3; and,

FIG. 9 is an enlarged front elevational view of a portion of the electronic device along the lines 9-9 and 9'-9' of FIG. 3. The broken lines illustrating portions of the electronic device form no part of the claimed design. The dot-dash broken lines defining the boundaries of the claimed design form no part of the claimed design. The dashed broken lines surrounding portions of the electronic device illustrated in the enlarged views in FIGS. 8 and 9 form no part of the claimed design.
